[57] **CLAIM**

The ornamental design for a unit for extending the functions of electronic computers, as shown and described.

DESCRIPTION

FIG. 1 is a top, front and right side perspective view of a unit for extending the functions of electronic computers showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being a mirror image; and,

FIG. 7 is a top, front and right side perspective view thereof showing the use of the apparatus.

The broken lines are shown for illustrative purposes only and form no part of the claimed design.
